US0D1078012S

(12) **United States Design Patent** (10) **Patent No.:** **US D1,078,012 S**
(45) **Date of Patent:** **** Jun. 3, 2025**

(54) **AROMATHERAPY MACHINE**

(71) Applicant: **Yang Hong**, Ji'an (CN)

(72) Inventor: **Yang Hong**, Ji'an (CN)

(**) Term: **15 Years**

(21) Appl. No.: **29/986,987**

(22) Filed: **Jan. 20, 2025**

(51) LOC (15) Cl. **23-04**

(52) U.S. Cl.

USPC **D23/368**; D23/366

(58) **Field of Classification Search**

(57) **CLAIM**

The ornamental design for an aromatherapy machine, as shown and described.

DESCRIPTION

FIG. 1 is a front perspective view of an aromatherapy machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the aromatherapy machine, which form no part of the claimed design.

1 Claim, 8 Drawing Sheets
